UNITED STATES PATENT OFFICE.

GEORGE W. HENRY, JR., OF PHILADELPHIA, PENNSYLVANIA, ASSIGNOR TO SOABAR COMPANY, OF PHILADELPHIA, PENNSYLVANIA, A CORPORATION OF PENNSYLVANIA.

TICKET-PRINTING MACHINE.

Application filed December 21, 1927. Serial No. 241,566.

My invention relates to certain improvements in machines for printing tickets such as are used on merchandise, indicating the size, price and style of the goods.

5 One object of my present invention is to provide a simple machine which can be operated by hand or by power, and which is so designed that a strip of tickets can be fed through the machine and printed, or a single 10 ticket can be placed in position and printed.

A further object of the invention is to design the machine that it can be operated by hand without disconnecting the power mechanism.

15 A still further object of the invention is to provide means for feeding the ticket to the printing position and to discharge the ticket after it has been printed.

In the accompanying drawings: Figure 1 is 20 a view of one side of my improved ticket-printing machine, the belt wheel being in section on the line 1—1; Fig. 3;

Fig. 2 is a view of the opposite side of the machine from that shown in Fig. 1, the feed 25 table being in section, and the door in the open position and partly broken away;

Fig. 3 is a front view;

Fig. 4 is a sectional elevation on the line 4—4 of Fig. 1;

30 Fig. 5 is a plan view;

Fig. 6 is a sectional view on the line 6—6 of Fig. 1;

Fig. 7 is a sectional view on the line 7—7, 35 Fig. 1;

Fig. 8 is a perspective of the feed pawl;

Fig. 9 is a view of a portion of a ticket strip used in this machine; and

Fig. 10 is a view of another form of ticket which can be printed in this type of machine.

40 Referring to the drawings, 1 is the base of the machine having a cylindrical casing 2. This casing is hollow and is provided at one side with a door having a pivot 3 and being secured in its closed position by a latch 4.

45 Within the casing is a spindle 6 on which is mounted a drum 7.

The ticket-strips *a* are wound upon paper tubes, one of which can be located on the drum 7, as shown in Figs. 2 and 4. The strip *a* extends through a slot in the casing and around a roller 8 mounted on a spindle 9, and is then passed through a slot 10 in a guide 11 and over the feed table 12 and over the platen 13. The guide in the present instance is made as 50 shown in Fig. 7.

The spindle 9 of the roller 8 is located in a bracket 14 projecting from the casing 2 and on this bracket is a pivot 15 for the lever 16, which carries at its outer end the type chase 17 which is adapted to a transverse slot in the head 18 of the hand lever 16. On this head is secured a handle by which the lever is operated. The lever 16 is held yieldably in a raised position by a coil spring 20 mounted on the pivot 15. One end of the spring bears 60 against the lever and the other end bears against a pin 21 projecting from the bracket 14.

The chase 17 has finger holds 22 by which it can be readily withdrawn from the head, a latch 23 retaining the chase in position. The standards 24 are secured to the rear of the feed table 12. Between the upper ends of the standards is a sleeve 25 and connected thereto by screws 26—26^a. The screw 26 forms a 70 pivot for a lever 27. The short arm of the lever 27 is connected by a link 28 to a pin 28^a on the hand lever 16.

A feed pawl is pivotally mounted on a pin 29 carried by the long arm of the lever. This 80 feed pawl is shown in Fig. 8 and has two fingers 31 which travel in grooves 32 in the feed table 12, Fig. 6. A spring 33 on the pin 29 tends to yieldingly hold the pawl in the grooves so that when the tag strip, shown in Fig. 8, is fed over the table, the fingers of the pawl extend into the notch *b* of the tag strip *a* and feed the tag strip forward.

In order to keep the tag strip on the table, a top guide 34 is provided. This guide is 90 yieldingly held on the block 11 by a spring 35 which bears against the underside of the head of a screw 36 screwed into the block, the block being recessed to receive the guide so as to prevent it moving laterally. The 95 pawl is notched at 37 so that it will pass freely over the top guide 34 as it is reciprocated.

In order to automatically ink the type, an 100 inking pad 39 is mounted on a frame 40 which is pivoted at 41 to the standards 24, the frame being connected by a link 42 to the hand lever 16. This link 42 has an adjustable section 44 by which the position of the inking pad in respect to the type can be regulated.

105 In order to limit the upward movement of the lever 16 and the position of the pawl, a set screw 45 is mounted in a lug in the bracket 14. This screw bears against the upper surface of the lever 16 when in its raised 110

position. A jam nut 46 locks the set screw in the position in which it is adjusted.

In order to operate the machine by power, a belt wheel 47 is mounted on a stud 48 projecting from the casing 2. The wheel, in the present instance, is a grooved wheel to receive a driving belt 49 which passes around a pulley 50 on an electric motor 51 of any suitable type. It will be understood that if a chain is used, instead of a belt, then the wheels 47 and 50 will be made accordingly. Cast integral with the wheel 47 is a cam 52 which bears against a roller 53 on a lever 54 pivoted to a bracket 55 secured to the casing 2. This bracket is slotted for the passage of securing bolts 56, so as to enable the bracket to be adjusted. The lever 54 is connected by a rod 57 to a pin 28^a on the hand lever 16.

The operation of the device is as follows:

20 If a coiled tag strip is used, it is mounted on the drum 7 and passed over the roller 8 through the slot 10 and over the table 12 and under the top guide 34 until one of the notches is in the path of the pawl 30, the proper type 25 is then assembled in the chase 17 and the chase is locked in position in the head of the lever 16. If the device is to be operated by hand, all that is necessary is to push down the lever 16 by the handle 19, which withdraws the 30 inking pad from under the type and withdraws also the feed pawl 30, allowing the type to make an impression on the tag that is located on the platen 13. The withdrawing of the pawl, as it recedes, drops 35 it into the notch *b* of the next tag, so that as the lever 16 is raised by the spring 20 the pawl will move the tag strip forward one tag, and the inking pad will be moved under the chase and will ink the type for the next impression.

40 If power is applied through a motor, then the rotation of the wheel 47 causes the cam 52 to depress the lever 54, and as this lever is connected to the hand lever 16 by the pin 57, it will automatically move the hand lever, 45 make the impression and feed the tag forward.

If it is desired to make an impression on a single tag such as shown in Fig. 9, then all that is necessary is to place the tag on the platen against the end of the pawl and depress the lever 16, which will print the tag, and the pawl, in its forward movement, will discharge the tag from the machine.

I claim:

55 1. The combination in a ticket-printing machine, of a base; a casing; means for supporting a roll of tickets within the casing; a bracket projecting from the casing; a lever pivoted to the bracket; a type chase mounted in the end of the lever; a platen mounted on the casing; a table back of the platen; a wheel located back of the table around which the strip of tags passes from the casing; a pawl for feeding the tags forward on the table; 60 means for connecting the pawl with the lever; 65 and a pivoted inking pad connected to the lever and arranged to ink the type carried by the chase when the lever is in its raised position and arranged to be withdrawn when the lever is depressed so that the type will make 70 an impression on a tag located on the platen.

2. The combination in a tag-printing machine, of a base; a casing mounted on the base; a bracket projecting from the casing; a lever pivotally mounted on the bracket; a type 75 chase carried by the lever; a platen mounted on the casing; a grooved table back of the platen; a slotted guide back of the table; a wheel around which a tag strip passes from the casing through the slot and under the 80 table; standards projecting from the block; a feed lever pivotally mounted on the standards; a link connecting said feed lever with the first-mentioned lever; and a pawl pivotally mounted on the opposite end of the feed 85 lever, said pawl having fingers adapted to grooves in the table, the pawl engaging a notched tag strip and arranged to feed the strip forward.

3. The combination of a base; a casing 90 mounted on the base, said casing having a bracket projecting therefrom; a lever pivotally mounted on the bracket; a spring tending to hold the lever in its raised position; an adjustable stop on the bracket for the 95 lever; a type chase mounted on the end of the lever; a handle on the lever by which it is depressed to make an impression; a fixed platen located on the frame under the type chase; a grooved table back of the platen 100 over which a tag strip is fed; means for holding the tag strip onto the table; a standard; a feed lever pivoted to the standard; a link connecting the lever with the hand lever; and a pawl yieldingly mounted on the opposite end of the feed lever and arranged to travel over the table, said pawl having fingers 105 extending into the grooves of the table and arranged to engage a tag strip and feed it forward to be printed.

4. The combination of a tag-printing machine; a base; a casing arranged to contain a rolled tag-strip; a bracket on the casing; a lever pivotally mounted on the bracket; a spring tending to raise the lever; a type chase mounted on the lever; a fixed platen on the casing; means for feeding the tag strip onto the platen; a spindle on the casing; a driving wheel on the spindle; a cam on said wheel; an operating lever pivoted on the casing; and a rod connecting the lever with said first-mentioned lever which carries the type chase, said last-mentioned lever being located under the cam so that as the wheel is turned the chase-carrying lever will be actuated, the parts being so arranged that the chase-carrying lever can be actuated by hand independent of the cam without disconnecting the mechanism.

5. The combination in a tag-printing ma-

chine, of a base; a casing; a drum located in the casing on which a coiled tag strip is mounted; a fixed platen on the casing; a table back of the platen; a slotted guide back 5 of the table, the tag strip being passed through the slot in the guide and onto the table and in position to be fed to the platen; a bracket on the casing; a lever pivoted to the bracket; a spring tending to hold the 10 lever in its raised position; a type chase carried by the lever; a standard; an inking pad pivoted to the standard; a link connecting the pivoted pad to the type chase so that the type chase will be withdrawn from under 15 the type when the chase-carrying lever is depressed; a feed lever pivoted to the standard; a pawl yieldingly mounted on the feed

lever and arranged to reciprocate over the table; a link connecting the lever with the chase-carrying lever; a stud on the casing; 20 a wheel mounted on the stud; a cam on the wheel; an adjustable bearing secured to the casing; an operating lever mounted on the bearing and having a roller resting against the underside of the cam; and a rod connecting the operating lever with the chase-carrying lever so that when the wheel is turned the chase-carrying lever will be automatically actuated, the parts being so arranged 25 that the chase-carrying lever can be actuated by hand independent of the cam mechanism without uncoupling any of the parts. 30
